UNITED STATES PATENT OFFICE.

L. SOLON GROUT, OF CHICAGO, ILLINOIS.

DESIGN FOR WATCH-SIGN.

SPECIFICATION forming part of Design No. 12,254, dated May 10, 1881,

Application filed December 7, 1880. Term of patent 3½ years.

To all whom it may concern:

Be it known that I, L. SOLON GROUT, a citizen of the United States, residing at Chicago, in the county of Cook and State of Illinois, have invented and produced a new and original Design for Watch-Signs, of which the following is a specification, reference being had to the accompanying drawings, forming part thereof, in which the figure represents an elevation of one side of my watch-sign.

The leading feature of my design consists in arranging on the periphery of the watch-disk, and on each side of the pendant, a figure representing Time. A frame resembling a pair of spectacles is attached to the lower edge of the disk, below such figures; but this frame can be omitted, if desired.

A is the disk, painted on each side to represent an open-face watch, and having pendant B, milled head a, and ring C.

D D' are the figures of Time, formed alike on each side, and secured to the periphery of the disk A, on opposite sides of the pendant

B. Each figure is represented as carrying a scythe or sickle, b.

The frame E, resembling a pair of spectacles, is secured directly to the lower edge of the disk A, but may be omitted.

The parts may be made of wood or metal, or both, in any suitable manner.

The sign is tastefully ornamented in colors and gold-leaf, and has the same appearance from either side.

1 claim—

The design for a watch-sign described, consisting of the disk A, representing on each side the open face of a watch, and the exterior sign-wings, D D', representing on each side similar figures of Time, facing each other from opposite sides of the pendant B, and ring C, substantially as shown.

L. SOLON GROUT.
